[57] CLAIM

The ornamental design for a bracket, as shown.

DESCRIPTION

FIG. 1 is a perspective view of a bracket showing my
design as seen from the front;
FIG. 2 is a side view of my design with the opposite side
being substantially a mirror image;
FIG. 3 is a top view thereof;
FIG. 4 is a bottom view thereof;
FIG. 5 is a front end view thereof; and
FIG. 6 is a rear end view thereof.
